[57] **CLAIM**

The ornamental design for a high-pressure, water lance handle, as shown and described.

DESCRIPTION

FIG. 1 is a left side view of the lance handle of the present invention with the safety released and the trigger in the engaged position;

FIG. 2 is a top view of the lance handle of the present invention;

FIG. 3 is a bottom view of the lance handle of the present invention;

FIG. 4 is a front view of the lance handle of the present invention;

FIG. 5 is a rear view of the lance handle of the present invention with the safety released;

FIG. 6 is a cross-section of the lance handle of the present invention through the line 6—6 of FIG. 1.

FIG. 7 is a left side view of the lance handle of the present invention with the safety engaged and the trigger locked in the disengaged position; and,

FIG. 8 is a rear view of the lance handle of the present invention with the safety engaged.

FIGS. 1 and 7 also represent mirror images of the right side of the lance handle of the present invention with the safety released in FIG. 1 and engaged in FIG. 7.
